UNITED STATES PATENT OFFICE.

HOWARD D. YODER, OF DETROIT, MICHIGAN, ASSIGNOR TO PENBERTHY INJECTOR COMPANY, OF DETROIT, MICHIGAN, A CORPORATION OF MICHIGAN.

EJECTOR.

Application filed July 3, 1922. Serial No. 572,661.

To all whom it may concern:

Be it known that I, HOWARD D. YODER, a citizen of the United States of America, residing at Detroit, in the county of Wayne and State of Michigan, have invented certain new and useful Improvements in Ejectors, of which the following is a specification, reference being had therein to the accompanying drawings.

10. The invention relates to ejectors of that type in which water under pressure is utilized for periodically ejecting drainage water from a sump or other receptacle. With such constructions it is usual to turn on or off the actuating water head by the operation of a float which is located in the sump. Thus the rise of water in the sump, by lifting the float, will open the supply valve and cause the operation of the ejector, while the lowering of the water in the sump by dropping the float will again close the supply valve and arrest further operation.

One difficulty which has been encountered in the operation of such mechanisms is the tendency for the float to assume a position where the supply valve is only slightly opened, thus interfering with the proper operation of the ejector and being wasteful of the water supply. To avoid this defect, I have provided means for temporarily delaying the movement of the float, both in its rising and falling, so as to secure a more positive action and a complete opening or closing of the valve. To this end the invention consists in the construction as hereininafter set forth.

In the drawings:

Figure 1 is a vertical central section through the ejector as arranged in a sump; 40 Figure 2 is a section on line 2-2 of Figure 1.

A is the sump or other receptacle in which the drainage water collects. B is the discharge conduit which extends centrally down in said sump and is supported by a standard C having a strainer D for protecting the inlet and also provided with a foot valve E for retaining sufficient water in the conduit B to expedite starting of the ejector. F is the ejector connected to the upper end of the conduit B and preferably extending laterally therefrom and communicating with an upwardly extending conduit section G, which leads to the point of dis-

charge. The ejector is provided with the 55 usual Venturi shaped chamber H and nozzle I which receives water under pressure from the supply conduit J. This supply is, however, controlled by a valve K which is normally closed and is only occasionally 60 opened when action of the ejector is required. L is the float for controlling action of the ejector, which, as shown, is sleeved upon the vertical conduit B. M is a lever for opening and closing the valve K, being pivotally 65 attached to the stem of said valve and having a fulcrum link N attaching it to the ejector casing and a pair of links O for attachment to the float L. The links O preferably 70 embrace the laterally projecting portion of the ejector casing F and are attached to the float by the pivot P and to the lever M by the pivot Q.

With the construction as thus far described, the rising of water in the sump will 75 lift the float L, which, through the links O and lever M, will open the valve K. This, by admitting water under pressure from the conduit J to the nozzle I, will start the ejector, creating a suction in the conduit B 80 which will draw upward the water in the sump. This by lowering the level in the sump will drop the float until the valve K is again closed.

The construction as just described is open 85 to the objection, before referred to, that the float may assume a position where the valve K is only slightly opened, so that the ejector is not efficiently operated while the water supply is wasted. To avoid this result, I 90 have made a simple attachment shown in detail in Figure 2. This consists of a pair of rollers R mounted in dogs S, which are attached to the opposite links O and project inward therefrom into interference with the 95 casing F. The dogs S are, however, resiliently yieldable, being held in normal position by the tension of a spring T extending therebetween, so that when sufficient pressure is exerted by the float in either an upward or downward direction, the rolls R will be forced by the casing F springing outward the dogs S. As specifically shown, the dogs S have their inwardly projecting portions carrying the rolls R passing 100 through central slots U in the links O, while the lower ends of said dogs are loosely secured by the headed ends P' and P'' of the 105

pivot pin P. There are also inwardly projecting flanges S' at the extreme lower ends of the dogs which form fulcrum bearings on the links O.

- 5 The links O are preferably arranged to embrace the portion of the ejector casing F, which forms the restriction of the Venturi passage, and to give mechanical strength to this portion of the casing it is provided 10 with ribs F'. These ribs cooperate with the rollers R to place a greater obstruction to the movement of the links than would be the case if they were engaged with a round conduit.
- 15 In the complete operation of the device, when the water rises in the sump, the float L can only rise to a point where the rollers R engage the casing F, this being insufficient to lift the valve K from its seat. As 20 the water continues to rise in the sump, it will eventually create sufficient upward pressure on the float to overcome the resistance of the rollers R, whereupon the spring T will yield, the dogs S moving outward and 25 the rollers R passing the ribs F'. When the resistance is overcome, the float will quickly rise to the higher level of water in the sump, in which position the valve K will be fully opened and the ejector set in operation.
- 30 This will discharge water from the sump, dropping the level, but the float is not permitted to immediately drop with the water, as the rollers R contacting with the ribs F' will still hold the float in raised position until the increasing weight again overcomes the tension of the spring T. As shown in 35 Figure 2, the links O are formed from a single bar return-bent at its upper end, as indicated at O'. Also, as shown in Figure 1, the 40 pivot Q, which attaches the lever M to the links, engages longitudinal slots O² in said links, permitting a certain amount of lost motion. Thus the float in rising and falling first takes up the lost motion between the 45 links and the lever, after which the dogs S come into action and restrain further movement, functioning in the manner previously described.

What I claim as my invention is:

- 50 1. The combination with an ejector, a valve for controlling the supply of actuating fluid thereto, and a float for operating said valve, of mechanical means cooperating with said float to delay the rising and falling thereof until a predetermined pressure is accumulated thereon, said means comprising a stationary member and a cooperating 55 member movable with said float, and connecting means between said valve and float 60 for transmitting the accumulated pressure

on the float to said valve for effecting a full movement thereof.

2. The combination with an ejector, of a valve for controlling the supply of actuating fluid thereto, a float for controlling the opening and closing of said valve, a pair of links for connecting said float to the valve, a stationary member between said links and spring-pressed dogs for engaging said stationary member to temporarily arrest movement of said links until pressure is accumulated to overcome the tension of the spring. 65 70

3. The combination with an ejector having a suction conduit, a discharge conduit and a supply conduit for the actuating fluid, 75 a float sleeved upon the suction conduit, a valve for controlling the actuating fluid, a pair of links connected to said float and to said valve embracing a portion of the discharge conduit, and spring-pressed dogs on 80 said links projecting inward therefrom into obstructive relation to said discharge conduit to delay the rising and falling of the float. 85

4. The combination with an ejector casing 90 having a suction conduit depending from a portion thereof and a discharge conduit rising from another portion, a supply conduit for the actuating fluid connected to said ejector, a valve for controlling the fluid supply, a float sleeved upon the suction conduit, a lever for actuating said valve extending above the ejector casing, a pair of links pivotally attached at their lower ends to said float and at their upper ends to said lever, 95 said links embracing said ejector casing, and spring-pressed dogs engaging said links and extending inward therefrom into obstructive relation to said ejector casing, whereby the rise and fall of said float is delayed. 100

5. The combination with an ejector casing having a contracted Venturi portion and external ribs for strengthening the same, a suction conduit for said ejector, a supply conduit for the actuating fluid, a valve for controlling said fluid supply, a float sleeved upon said suction conduit, a pair of links connected to said float and embracing the ribbed portion of said ejector casing, a lever for connecting the upper ends of said links 110 to said valve, dogs secured to said links projecting inward therefrom provided with rollers for engaging said ribbed casing, and a spring for yieldably drawing said dogs inward into obstructive relation to said casing, whereby the rise and fall of the float 115 is delayed.

In testimony whereof I affix my signature.

HOWARD D. YODER.
